(57) **CLAIM**

The ornamental design for a receptacle for trash, refuse, recycling, or the like, as shown and described.

DESCRIPTION

FIG. 1 is a perspective view of a receptacle for trash, refuse, recycling, or the like showing an embodiment of my new design;

FIG. 2 is a front elevation view thereof, the rear elevation being a mirror image thereof;

FIG. 3 is a top plan view thereof;

FIG. 4 is a bottom plan view thereof;

FIG. 5 is a left side elevation view thereof, the right side elevation view being a mirror image thereof;

FIG. 6 is a perspective view of a receptacle for trash, refuse, recycling, or the like showing an embodiment of my new design;

FIG. 7 is a front elevation view thereof, the rear elevation being a mirror image thereof;

FIG. 8 is a top plan view thereof;

FIG. 9 is a bottom plan view thereof; and,

FIG. 10 is a left side elevation view thereof, the right side elevation view being a mirror image thereof.

The broken lines around the perimeter of the handle recesses of FIGS. 2 and 7 and the bottom of FIGS. 4 and 9 define boundaries to disclaim the handle recesses and the bottom surfaces from the claimed design and form no part of the claimed design.
